NARROW TAPE ROBOTYPER

Janice S. Grant, South Glastonbury, Conn., assignor to
Royal McBee Corporation, Port Chester, N. Y., a cor-
poration of New York

Application December 10, 1957, Serial No. 48,853

Term of patent 7 years

(Cl. D26—5)

Fig. 1

Fig.2

Fig. 1 is a front perspective view of the narrow tape robotyper showing my new design, and,

Fig. 2 is a rear perspective view of the narrow tape robotyper shown in Fig. 1.

The broken line showing of a typewriter is for illustrative purposes only.

I claim:

The ornamental design for a narrow tape robotyper, as shown and described.
